UNITED STATES PATENT OFFICE.

JOHN H. GEORGE, OF BRIDGEPORT, CONNECTICUT, ASSIGNOR TO HAWTHORNE MANUFACTURING COMPANY, INCORPORATED, OF BRIDGEPORT, CONNECTICUT, A CORPORATION OF CONNECTICUT.

ADAPTER FOR ELECTRIC SOCKETS.

1,187,723.

Specification of Letters Patent. Patented June 20, 1916.

Application filed October 15, 1913. Serial No. 795,364.

To all whom it may concern:

Be it known that I, JOHN H. GEORGE, a subject of the King of England, and a resident of Bridgeport, county of Fairfield, and State of Connecticut, have invented an Improvement in Adapters for Electric Sockets, of which the following description, in connection with the accompanying drawings, is a specification, like characters on the drawings representing like parts.

This invention relates to adapters for electric sockets, and more especially to an adapter for adapting a socket of one type to a lamp of another type. Lighting systems for motor bicycles and motor cars are of two general types, viz: the two-wire system and the single-wire system. In the latter type, a single wire cable is connected to one lamp terminal, while the other lamp terminal is grounded upon the metal frame of the bicycle or car. The single-wire system is a comparatively recent development, while the two-wire system is the more generally employed. In connection with such systems, there is commonly employed a special type of lamp and socket, the latter being provided with a pair of bayonet slots, and the lamp being provided with a pair of laterally projecting pins located in the slots. In the so-called single-wire system, a single spring-pressed pin forms one conductor of the socket, and presses against a centrally disposed lamp terminal, and the socket member constitutes the other conductor, and receives the lamp-shell which forms the other terminal of the lamp. In the two-wire system, the socket is provided with two spring-pressed pins constituting conductors, which press against two lamp terminals, both of which are insulated from the lamp-shell. The adapter which forms the subject matter of this invention enables a lamp of either type to be used with a socket of the other type, by the simple introduction of the adapter between the lamp terminal or terminals and the spring-pressed pin or pins of the socket.

My invention will be best understood by reference to the following specification, when taken in connection with the accompanying drawings of one specific embodiment thereof, while its scope will be more particularly pointed out in the appended claims.

In the drawings: Figure 1 is a plan of one side of one form of adapter embodying my invention; Fig. 2 is a plan of the opposite side of the adapter; Fig. 3 is a central sectional view of the adapter as applied to a two-wire type of socket and a single-wire type of lamp; Fig. 4 is an elevation of the parts shown in Fig. 3; and Fig. 5 is a sectional view similar to Fig. 3, showing the adapter as applied to a single-wire type of socket and a two-wire type of lamp.

Referring to the drawings, and to the specific adapter which I have selected for illustrative purposes, I have there shown an insulating plate, preferably in the form of a disk 6, of fiber, rubber, or other suitable insulating material, to which two conductors 7 and 8 are secured. The conductor 7 has two contact portions 9 and 10, located on opposite faces, respectively, of the insulating disk, the contact portion 9 being centrally located, while the contact portion 10 is disposed at one side of the center of the disk. The conductor 7 may be secured to the insulating disk in any other appropriate manner, but herein extends through a hole 11 in the disk, and its contact portions extend from the hole toward the center of the disk.

The conductor 8 has a contact portion 12, disposed on the same side of the disk as the contact portion 10 of the other conductor 7. The conductor 8 may be secured to the disk in any other appropriate manner, but herein is provided with two tongues or prongs 13 and 13, bent so as to overlie the edge of the disk and the margin of its opposite face. The conductor is further provided with two tongues or prongs 14 and 14, bent so as to overlie the edge of the disk and the margin of its opposite face. Preferably, the tongues 13, 13 are disposed comparatively close together at one side of the center of the disk, while the tongues 14, 14 are disposed on opposite sides of the disk, preferably adjacent diametrically opposite points in the circumference of the disk, and somewhat beyond the opposite side of the center of the disk, as compared with the location of the other pair of tongues. This disposition of the tongues insures the conductor 8 being securely held in its place upon the disk.

The adapter may be held against turning movement in the socket by any suitable

means, but herein is provided with means comprising one or more lugs adapted to interengage with the socket. Herein, two such lugs, 15, 15, are employed, and are formed on the conductor 8 at diametrically opposite points, and arranged to engage the socket as described presently.

The lamps and sockets shown in the drawings are commercial types, except that in the 10 case of the socket, a slight modification is herein made, as hereinafter described. In Fig. 3, there is shown a so-called two-wire type of socket 16, and a single-wire type of lamp 17, while in Fig. 5 there is shown a 15 single-wire type of socket 18, and a two-wire type of lamp 19.

Referring to Fig. 3, the socket 16 contains two spring pressed pins 20 and 21, which, in practice, are connected to and form the terminals of two line wires leading to the 20 source of current. The socket is provided with a pair of bayonet slots 22, 22. The lamp 17 is provided with a metallic shell 23, inserted in the socket and having a pair of 25 laterally projecting pins 24, 24, extending into the bayonet slots 22, 22, respectively.

The adapter is simply introduced between the spring-pressed pins 20 and 21, and a terminal 25 on the end of the lamp, and in this 30 way the spring-pressed pins are maintained in contact with the contact portions 10 and 12 of the conductors 7 and 8, and the spring-pressed pins serve to maintain the contact portion 9 of the conductor 7 in contact with 35 the lamp terminal 25. The other terminal of the lamp is formed by the metallic shell 23, which is in electrical contact with the socket tube. The conductor 8 is in electrical contact with the socket tube, as well as with 40 the spring-pressed pin 21, and hence the connection from the pin is completed to the lampshell by the socket.

As before stated, the lugs 15, 15 project laterally into the bayonet slots 22, 22, and 45 the latter are prolonged beyond their usual length, *i. e.*, beyond their offset portions as shown in Fig. 3, to accommodate the lugs, whereby the latter serve to hold the adapter against rotation when the lamp is rotated. 50 It will now be apparent that the spring-pressed pins still perform their usual functions of holding the pins 24 firmly seated in the offset portions of the bayonet slots 22, but contact with the conductors of the 55 adapter, and thus cause the latter to complete the connection with a lamp of the single-wire type.

Referring now to Fig. 5, the socket 18 is provided with a single spring-pressed pin 60 26, insulated from the socket tube and pressing against the contact portion 10 of the adapter, which latter, in this case, is inverted. The lamp 19 is provided with terminals 27 and 28, which bear, respectively, 65 against the contact portions 9 and 12. In

this case, also, the spring-pressed pin performs its usual functions, but the adapter is simply interposed between the pin and the lamp terminals, and maintains the necessary electrical connection. It will be understood 70 that, in this case also, the conductor 8 is in contact adjacent the edge of the disk with the metallic socket tube 18 forming a part of the circuit. In this form of socket, also, there are provided the usual bayonet slots 75 and pins, which it will be unnecessary to show or to describe, except to say that the slots will receive the lugs of the adapter as already described in connection with the previous example. 80

It must now be entirely clear that by the simple expedient of inserting the adapter, and slightly elongating the slots of the socket, the latter, when of either type, can be readily adapted to the use of a lamp of the 85 other type at slight expense.

While I have herein shown and described one specific form or embodiment of my invention for illustrative purposes, and have disclosed and discussed in detail the construction and arrangement incidental to one specific application thereof, it is to be understood that the invention is limited neither to the mere details or relative arrangement of parts, nor to its specific embodiment herein 95 shown, but that extensive deviation from the illustrated form or embodiment of the invention may be made, without departing from the principles thereof.

Having thus described my invention, what 100 I claim and desire by Letters Patent to procure is:

1. As a new article of manufacture, an adapter for electric sockets having two conductors insulated from each other, said conductors having each a contact on one face of the adapter, each of said contacts being non-centrally located, one of said conductors having a contact on the opposite face of 105 said adapter, the other conductor having also a contact adjacent the side of said adapter.

2. An adapter for electric sockets, comprising, in combination, an insulating disk having a centrally-located insulating portion, and a pair of conductors one of which has a contact portion centrally located on one face of the disk and another contact portion non-centrally located on the other face of said disk, and the other of which has a contact portion on one face only of 110 said disk and another contact portion adjacent the edge of said disk.

3. An adapter for electric sockets comprising, in combination, an insulating disk, and a pair of conductors one of which extends through said disk at one side of the center of the latter and has a contact portion located centrally on one face of the disk 125 and another contact portion non-centrally 130

located on the other face of said disk, and the other of which has a contact portion on one face only of said disk and another contact portion adjacent the edge of said disk.

5 4. An adapter for electric sockets comprising, in combination, an insulating disk, and a pair of conductors one of which has a centrally located contact portion on one face of said disk, the other conductor having a 10 contact adjacent the edge of said disk, both of said conductors having contact portions each of which is disposed at one side of the central portion of said disk on the opposite face of said disk, the latter face having at 15 its central portion insulating material interposed between the last-mentioned contact portions.

5. An adapter for electric sockets comprising, in combination, an insulating disk, 20 and a pair of conductors one of which has a centrally located contact on one face of said disk and extends through said disk at one side of the center of the latter to the other face where it has another contact portion located entirely at one side of the center of the disk, the other conductor having a contact portion also on the latter face of said disk at one side of its center and another contact adjacent the edge of said disk.

25 6. An adapter for electric sockets comprising, in combination, an insulating disk, and a pair of conductors one of which has a centrally located contact on one face of said disk and extends through said disk to 30 the other face where it has another contact portion at one side of the center of the disk, the other conductor having a contact portion also on the latter face of the disk at one side of its center, and prongs lapped 35 over the margin of the disk.

7. An adapter for electric sockets comprising, in combination, an insulating disk, and a pair of conductors one of which has a centrally located contact on one face of 40 said disk and extends through said disk to the other face where it has another contact portion at one side of the center of the disk, the other conductor having a contact portion also on the latter face of the disk at one 45 side of its center, and a plurality of prongs two of which are lapped over the margin of said disk adjacent substantially diametrically opposite points in its perimeter.

8. The combination with a socket member constituting a conductor having a lamp-receiving opening, of an adapter comprising an insulating disk disposed within said opening, and two conductors one of which has contact portions on both faces of said disk and the other of which contacts with 55 said socket member and has a contact portion on one face of said disk. 60

9. The combination with a socket member constituting a conductor having a lamp-receiving opening, of an adapter comprising 65 an insulating disk disposed within said opening, two conductors one of which has contact portions on both faces of said disk and the other of which contacts with said socket member and has a contact portion 70 on one face of said disk, and means to hold said disk against turning movement with relation to said socket.

10. The combination with a socket member constituting a conductor having a lamp-receiving opening, of an adapter comprising 75 an insulating disk disposed within said opening and two conductors one of which has contact portions on both faces of said disk and the other of which contacts with 80 said socket member and has a contact portion on one face of said disk, one of said conductors having means interlocking with said socket to prevent said disk and its conductors from turning with relation to said 85 socket member.

11. The combination with a socket member constituting a conductor having a lamp-receiving opening, of an adapter comprising 90 an insulating disk disposed within said opening, and two conductors one of which has contact portions on both faces of said disk and the other of which contacts with said socket member and has a contact portion 95 on one face of said disk, one of said conductors being provided with a lug projecting beyond the margin of said disk, said socket member being provided with a slot in which said lug is disposed.

In testimony whereof, I have signed my 100 name to this specification, in the presence of two subscribing witnesses.

JOHN H. GEORGE.
